UNITED STATES PATENT OFFICE.

REGINALD A. FESSENDEN, OF BRANT ROCK, MASSACHUSETTS, ASSIGNOR TO NATIONAL ELECTRIC SIGNALING COMPANY, OF PITTSBURG, PENNSYLVANIA, A CORPORATION OF NEW JERSEY.

ELECTRICAL SIGNALING.

1,002,052.

Specification of Letters Patent. Patented Aug. 29, 1911.

Application filed December 23, 1907. Serial No. 407,749.

To all whom it may concern:

Be it known that I, REGINALD A. FESSENDEN, a citizen of the United States, residing at Brant Rock, in the county of 5 Plymouth, State of Massachusetts, have invented certain new and useful Improvements in Electrical Signaling, of which improvements the following is a specification.

My invention relates to telephone transmitters.

In the accompanying drawings forming a part of this specification Figure 1 shows an arrangement of apparatus suitable for carrying out the invention, where the transmitter is actuated directly by the voice and Fig. 2 a suitable arrangement where the transmitter is actuated by an electro-magnet.

The invention herein disclosed has for its object the securing of greater efficiency in 20 the production of electrical impulses by means of slight changes of pressure, whether produced directly or indirectly by sound waves or by any other means.

When certain classes of substances, for example silicon and tellurium, are used to form 25 one element of a contact and are brought into perfect non-microphonic contact with another conductor, such as brass, the contacts so formed are capable of acting either thermoelectrically or as rectifiers, according 30 to the amount of pressure used, and where a local battery is also used, according to the intensity of local battery used. With the majority of these substances the thermo-electric current produced is in the opposite 35 direction to the current produced by the rectifying action. The writer has discovered that a sensitive telephone transmitter may be constructed by using such a contact and suitably adjusting the pressure, and, 40 where a local battery is used, suitably adjusting the current from the local battery.

In Fig. 1, 11 is the diaphragm of a telephone transmitter attached to which is a small conducting rod 12, which may be of brass, the outer end of which is preferably rounded. The outer end of the rod 12 rests against a button 13 which may be of silicon, said button being fastened to the brass disk 14. The brass disk 14 is mounted on the flexible arm 15, and the pressure between 13 and 12 is adjustable by means of the screw 16.

55 17 is a local battery adjustable by means of the sliding contact 22.

18 is the secondary of a transformer whose primary 20 is connected to a high frequency alternator 19.

21 is a telephone receiver.

On suitably adjusting the transmitter, and talking into the mouth piece so as to set the diaphragm 11 into vibration, and thus vary the pressure between 13 and 12, the speech is reproduced in the receiver 21.

I do not limit myself to the employment 65 of a single contact as more than one contact may be used.

In Fig. 2 the diaphragm 11 instead of being actuated directly by the voice is actuated by the current in the circuit 26, 24, 24', 27, 70 where the pressure is adjusted by means of the screw 23 and the silicon button 13 is placed on the diaphragm, with the brass rod 12 pressing against it. The high frequency alternator and transformer shown in Fig. 1 75 are omitted, not being essential. On signals being transmitted through the circuit 26, 24, 24', 27 they are rendered audible in the receiver 21.

By the term "self responsive contact" is 80 meant a contact which, having its opposite elements connected to an indicating mechanism without any local battery being in the circuit, will produce an indication when a high frequency current is caused to pass 85 through the contact.

Having thus described my invention and illustrated its use, what I claim as new and desire to secure by Letters Patent is the following:

1. In a system of electrical signaling, a transmitter comprising a self responsive good contact of different materials, means for varying the pressure of the contact by 95 means of the impulses to be transmitted, a local circuit containing the contact and an indicating mechanism.

2. A telephone transmitter comprising a motor element carrying an electrode of low 100 resistance, a terminal in contact therewith composed of an element of high specific resistance and with thermoelectric power, devices for passing a current through said contact, and an indicating instrument in circuit operated by changes of current due to the action of the thermo-couple, substantially as described.

3. A transmitter for electric signaling comprising a pair of terminals in good contact composed of material to generate cur-

rent, a vibrator connected with one of said terminals, means to pass a current through the contact, and an indicating instrument in circuit with the contact adapted to be actuated by variations of the current generated in the contact.

4. A telephone transmitter comprising a pair of mechanically separate electrodes of different materials in good or non-microphonic contact, and adapted, by characteristics of the members, to respond automatically to variations of pressure between them.

5. A telephone transmitter comprising a

thermo-couple of separate electrodes in non-microphonic contact, means to vary the pressure in accordance with sound waves and an indicating instrument operated by changes of current strength in a circuit including the thermo-couple.

In testimony whereof I have hereunder signed my name in the presence of the subscribed witnesses.

REGINALD A. FESSENDEN.
